UNITED STATES PATENT OFFICE

172,517

REFRIGERATED DISPLAY CASE

Sheldon Rutter, Evanston, Ill., assignor to Tyler
Refrigeration Corporation, Niles, Mich., a corporation of Michigan

Application February 11, 1954, Serial No. 28,963

Term of patent 7 years

(Cl. D80—11)

To all whom it may concern:

Be it known that I, Sheldon Rutter, a citizen of the United States, residing at Evanston, in the county of Cook and State of Illinois, have invented a new, original, and ornamental design for a Refrigerated Display Case, of which the following is a specification, reference being had to the accompanying drawing, forming part thereof.

Fig. 1 is a perspective view of a refrigerated display case, showing my new design.

Fig. 2 is a front elevation of the same, and Fig. 3 is an end elevation of the same.

The end not shown is the same as that which is illustrated. The back is plain and unornamented.

I claim:

The ornamental design for a refrigerated display case, as shown and described.
